UNITED STATES PATENT OFFICE

CLARENCE E. DUNLAP, OF SIOUX CITY, IOWA

TIRE-PATCH APPLIER

Application filed January 31, 1929. Serial No. 336,570.

My invention relates to a method of, and machine for applying, tube or casing patches of the preformed type, such as is shown in my Patent No. 1,756,183, covering a pre-formed patch. My method involves the use of high, uniformly applied, pressure in applying the patch.

A particular object of my invention is to provide a machine particularly adapted to apply the patch disclosed in said application.

Another object of my invention is to provide such a machine in which the pressure may be applied uniformly to the bevelled edges of the patch.

15 A still further object is to provide such a machine which may be operated very rapidly without losing its accuracy.

More particularly referring to the last object, it is my purpose to provide a machine including a plunger, together with means to receive and support the patch in proper position relative to the plunger, preparatory to attaching the patch to a tube.

25 With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a side elevation of the machine.

Fig. 2 is a rear elevation of the same.

27 Fig. 3 is a vertical, central, sectional view through the operative portions of the machine.

Fig. 4 is a similar view showing the plunger in a slightly different position.

42 Fig. 5 is an enlarged view of the end of the plunger and supporting sleeve.

Fig. 6 shows a slightly modified form of a plunger.

45 The application of a preformed patch having a bevelled edge to a tube to be repaired, where it is desired to apply the patch under pressure, involves several problems, one growing out of the other. In the first place, the most important requisite in applying a patch to a tube is that the patch be securely united to the tube, particularly at its edges.

The object of the bevelled edge is to minimize peeling of the patch under the effects of friction between the tubes and casing and so the bevelled feature is very important in a patch. Due to this problem of peeling, it is 55 most important that the patch be securely united at its edge to the tube. While the bevelled feature is thus very essential, it introduces the problem of properly applying pressure to the patch by means of a machine 60 so that the edges of the patch may be securely united.

In order to meet this problem, I have provided a machine embodying a plunger having a matrix with a cross sectional shape and area corresponding to the peripheral shape of the patch, the matrix being dished so as to exactly fit the vertical, cross sectional contour of the patch. In this way, pressure may be applied to the patch over the flat surface 70 thereof and also to the bevelled face up to the edge of the patch.

The employment of this type of plunger raises the problem, however, of registering the patch accurately with the plunger so that 75 the pressure of the plunger may be properly applied. If the patch were first adhered to the tube, it would be rather difficult to adjust the tube in the machine so as to bring the plunger in exact register with the patch and if the plunger is only slightly out of register with the patch, the pressure will be so improperly applied as to give very negative results.

To meet this problem, I provide means for 85 attaching the patch to the end of the plunger in proper register with the plunger, the patch to be carried downwardly with the plunger toward the area of the tube to which it is to be applied and to be brought into contact 90 with the tube by the plunger.

A requirement of this device is that it be so constructed that it will not interfere with the application of pressure to the patch by the plunger, although capable of securely holding the patch in its proper position up to the point of contact of the patch with the tube.

In the accompanying drawings, I have used the reference character 10 to indicate generally the base of the machine of my in-

vention. Cast integrally with the base is an upwardly projecting arm 11, which is extended forwardly as at 12 over the plate 13, which also is formed integrally with the base.

- 5 A vertically disposed bearing sleeve 14 is formed on the end of the arm 12. The bearing sleeve 14 is provided at its lower extremity with an inwardly extending collar 15, in which slides the shaft 16 of the plunger.
- 10 The head 17 of the plunger slides within the bore of the sleeve 14. A shoulder 18 is formed between the head 17 and the shaft 16 of the plunger and the spring 19 is received between the shoulder 18 and the collar 15 encircling the shaft 16. A pair of ears 20 extend upwardly from the upper end of the sleeve 14 and support a pin 21, upon which is journaled a cam shaped shoe 22 for applying pressure to the plunger. A lever 23 projects from the shoe 22 and movement of the lever in the direction indicated by the arrow 24 brings the extended portion of the shoe 25 downwardly against the head 17, causing the plunger 16 to move downwardly.

The cam face of the shoe 22 is divided generally into the portion 25, adapted to give rapid downward movement to the plunger and the portion 26, which is substantially on the surface of a cylinder coaxial with the pin 21, adapted to apply pressure to the plunger after it has reached a position where the patch is in contact with the tube.

The lower end of the plunger is formed as a matrix having a flat, central face 27 to engage the flat, upper face 28 of the patch and having the downwardly extended, dished side face 29, adapted to engage the bevelled face 30 of the patch.

30 It may be noted at this point that the patch comprises an upper vulcanized layer and a lower unvulcanized layer 31, the edge of which is cut perpendicularly, all as described in the co-pending application mentioned hereinbefore.

In order to support the patch in contact with the matrix of the plunger, I provide a supporting sleeve 32, which is freely slidable upon the lower end of the plunger and supported by a pin 33, the sleeve 32 being provided with vertical slots 34 (Fig. 1) to allow sliding movement of the sleeve.

50 A collar 35 is secured to the shaft 16 and spaced above the sleeve 32 and a spring 36 is received between the collar 35 and the sleeve 32 to urge the sleeve downwardly.

In the operation of the machine, the tube 37 is extended flat over the plate 13 with the puncture 38 centered beneath the plunger. A coating of cement 39 is applied to the surface of the tube surrounding the puncture after proper buffering and cleaning of the tube and may be either left in place, or the excess scraped off. It will be understood that the use of cement does not form a material ele-

ment of this invention. One of the patches is pressed upwardly into the cavity formed between the matrix of the plunger and the sleeve 22, where it will be held by the engagement of the vertical edges of the layer 31 against the inner surface of the sleeve 22.

70 After removal of the protective covering of the patch (not shown), which is preferably done before the patch has been secured to the plunger, the lever 23 is brought forwardly and downwardly, the tube being adjusted as the plunger descends to bring the puncture to the desired position relative to the plunger.

75 The lower edge of the sleeve 22 will first engage the tube and in so doing serve to secure the tube against further movement relative to the plate 13, thus assuring a direct downward pressure against the tube by the patch. As further pressure is brought against the lever 23, the plunger will continue to descend, sliding within the sleeve 32, the latter being allowed to recede relative to the plunger and compressing the spring 36 in so doing.

80 Thus the sleeve 32 will be snugly retained in engagement with the tube as the plunger descends, positively preventing any side slipping of the patch relative to the plunger as pressure is brought to bear against the patch. The flat face 27 will exert pressure against the central portion of the patch and the dished face 29 will exert the same amount of pressure against the bevelled face 30 of the patch, thus securing the patch with equal 85 pressure over its entire surface including the extreme edge of the patch.

85 A patch so applied is about as effective as a vulcanized patch, all uncertainties in the method of application of the patch being entirely removed by the use of the machine. The machine is small enough so that it may be carried in a tool kit and is simple and inexpensive in construction.

90 There is a very material difference in the result obtained by using the type of pressure disclosed in this application and the type of pressure which has heretofore been obtained by hand (the fingers of the operator). In the first place, it is possible to obtain a much higher pressure by means of the machine; in the second place, the pressure is uniform over the entire surface of the patch, and in the third place, the pressure is applied to the bevelled edge as well as the remainder of the patch.

95 One result of this type of pressure is that of insuring against any of the cement being allowed to remain between the patch and the tube. The uniform high pressure will squeeze out all of the cement except that which enters the pores of the rubber and will bring the surfaces of the patch and tube into intimate contact with each other. The pressure that can be obtained with the ma-

chine disclosed, wherein the lever is about fourteen inches in length will range from 1500 to 2000 pounds per square inch. By using a longer lever, higher pressures may be 5 obtained.

As far as I am aware, I am the first to conceive of a machine or a high pressure process for applying a bevelled patch to a tube. It is not my intention to claim a machine or 10 process for applying an unbevelled patch except in that feature of the machine wherein the patch is held by the plunger prior to the application of the patch to the tube. It will be understood that this principle of 15 securing the patch to the plunger in register with the face of the plunger is applicable also to an unbevelled patch and that the same advantages will be derived, although to a lesser extent; that is, this feature is not as 20 essential to a process of applying unbevelled patches as it is to the bevelled patch.

It will be understood that the plunger might be formed in two parts instead of integrally. For instance, in Fig. 6, the plunger 25 shaft 16 is shown provided at its lower end with an enlarged head 41, which may be secured in any manner to the shaft 16, as by means of the set screw 40. The sleeve 32 is mounted on the head 41, the collar 35a is 30 formed on the head 41, and the spring 36 is mounted between the collar 35a and sleeve 32 in the same manner as in the other form of my invention. Such a removable head is desirable where the machine is to be used for 35 several sizes of patches, different sized heads being employed. The head shown would be particularly adaptable for use in connection with the casing patches.

Where the term "plunger" is used in the 40 claims, it is intended to cover a plunger, whether made integrally as in Figs. 1-5 inclusive, or in two parts, including a removable head, as in Fig. 6.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a machine for applying bevelled tube or casing patches, a base including a flat plate, 55 a bearing supported by the base over said plate, a plunger having a matrix, dished to conform to the cross sectional contour of a patch, the plunger being axially slid able in said bearing, the matrix being adapted to cooperate with the plate, means to apply high pressure to said plunger, and a sleeve carried by the plunger having an interior, cross sectional shape and area such that it will snugly receive and support a patch in register 60 with the matrix, said sleeve being capable of

recession under pressure of the plunger against a tube or casing supported on the plate.

2. In a machine for applying bevelled tube or casing patches, a base including a flat plate, 70 a bearing supported by the base over said plate, a plunger having a matrix, dished to conform to the cross sectional contour of a patch, the plunger being axially slid able in said bearing, the matrix being adapted to cooperate with the plate, means to apply high pressure to said plunger, and means to support a patch in register with the matrix, said means being capable of recession under pressure of the plunger against a tube supported 75 on the plate.

3. In a machine for applying patches, a base including a flat plate, a bearing supported by the base over said plate, a plunger, 80 axially slid able in said bearing, and having a working end to cooperate with the plate, and means to support a patch against the working end face of the plunger, said means being capable of recession upon pressure of the plunger against a tube supported on said 85 plate.

4. In a machine for applying patches, a base including a flat plate, a bearing supported by the base over said plate, a plunger, 90 axially slid able in said bearing, and having a working end to cooperate with the plate, and means to support a patch against the working end face of the plunger, comprising a sleeve encircling and slidably mounted on the plunger and normally projecting beyond the working end to form a cavity in which the patch may be received, and means for resiliently urging the sleeve toward said 95 normal position, said last means allowing recession of the sleeve under pressure of the plunger against a tube supported upon the tube.

5. In a machine for applying patches, a base including a flat plate, a bearing supported by the base over said plate, a plunger, 100 axially slid able in said bearing, and having a working end to cooperate with the plate, and means to support a patch against the working end face of the plunger, comprising a sleeve encircling and slidably mounted 105 on the plunger and normally projecting beyond the working end to form a cavity in which the patch may be received, a collar on the plunger and spaced from the sleeve, and a coil spring encircling the plunger between the sleeve and collar, said coil spring allowing recession of the sleeve under pressure of the plunger against a tube supported 110 upon the plate.

Signed this 26th day of January, 1929, in 115 the county of Woodbury and State of Iowa.

CLARENCE E. DUNLAP.
